AUTOMATIC PUMP AND AGITATOR,
APPLICATION FILED FEB. 17, 1914.

Patented Oct. 16, 1917.

3 SHEETS—SHEET 3.

UNITED STATES PATENT OFFICE.

CHARLES E. HOPKINS, OF NEW YORK, N. Y.

AUTOMATIC PUMP AND AGITATOR.

1,242,939.

Specification of Letters Patent. Patented Oct. 16, 1917.

Application filed February 17, 1914. Serial No. 819,210.

To all whom it may concern:

Be it known that I, CHARLES E. HOPKINS, a citizen of the United States, residing at New York, in the county of New York and State of New York, have invented a new and useful Automatic Pump and Agitator, of which the following is a specification.

This invention relates to apparatus for the purpose of handling and mixing soft metal or other substances, and is particularly intended for use in casting stereotype plates.

The principal objects of the invention are to secure a continuous flow of metal through the pump spout to and through an overflow, for the purpose of maintaining the metal in the spout at a given height; and to provide means for controlling the overflow, and means for regulating the controlling means; means for causing the metal to advance above the overflow to and out through a nozzle under a given pressure, and automatic means for stopping said flow after discharging a stated amount.

The invention is fully shown in the accompanying drawings in which,

Figure 1 is a side elevation of a pump constructed according to this invention located in a pot positioned in a furnace, the pot and furnace being sectioned.

Fig. 2 is a plan of the same.

Fig. 3 is a front view showing only so much of the pump mechanism as will be seen above the pot.

Fig. 4 is a longitudinal sectional view on the line 4-4 of Fig. 2.

Fig. 5 is a rear view of the pump with a portion of the spout and the overflow sectioned on the same line.

Fig. 6 is a plan view of the gear pump mechanism and shows the agitator blades located in the large gear, sectioned on line 6-6 of Fig. 5, and

Fig. 7 is a plan view of the pump casing.

The pump and agitating mechanism is held suspended within and at one side of the pot 10 by rods 11, extending down to the pump case 12 from a shelf 13, forming part of a bracket 14, fast on the pot's rim.

The pump mechanism consists of two gear wheels 15 and 16, operating in mesh at the rear of a receiving chamber 17. The larger gear 15 is mounted on a stud fixed in the pump casing 12, and is provided with angular blades 18 instead of spokes. Each blade

draws the liquid substance through and upward as the gear wheel is revolved and thereby mixes the said substance or metal by agitating it. The opposite gear wheel 16 is made about one half the size of the 60 agitator gear wheel 15, and is mounted on the lower end of a vertical shaft 19, extending up through a bearing in the casing 12, and through a bearing formed in the bracket shelf 13. A bevel gear 20 is mounted on 65 the upper end of the gear shaft 19, and a like gear 21 is made fast on a cross shaft 22, which operates in bearings on the shelf 13. To one end of this cross shaft is fast a driving pulley 23, through which the 70 pump gears are kept in constant rotation.

The pump case 12 is formed with the receiving chamber 17. (Fig. 6). The gear wheels are so located that a portion of their toothed faces extends within the receiving chamber, the walls 25 and 26 of which are made to overlap a portion of the top and bottom sides of the gear rims, and the vertical walls 27 and 28 engage the faces of the teeth. By this means the revolving of the 80 gear teeth toward the receiving chamber draws the molten metal between the teeth, past the walls 27 and 28, into the chamber, and owing to the gears being in mesh the metal is prevented from passing out with 85 the teeth.

The receiving chamber 17 extends up and is provided with a seat 29, in which is positioned one end of a pivoted spout 29^a, formed so as to curve out over the edge of 90 the pot 10; the loose end of the spout is provided with a discharge nozzle 30, shaped to conform with the opening of a casting box.

Located near or above the edge of the pot 95 10, but below the discharge nozzle 30, is an overflow pipe 31, (see Fig. 5). This overflow pipe extends downward into the pot, and is formed at its bottom with a valve seat; a valve plunger 32, mounted on a rod 33, is positioned beneath the valve seat. As the metal is continuous in its flow through the pump gears into the chamber, and up the spout to the overflow, down which it falls, it will be seen that the closing of the 100 valve would stop the flow and cause the metal to advance up the spout and out of the nozzle.

The valve is closed by raising the plunger 32 into engagement with its seat on the over- 110

flow 31, whereupon, as above stated, the metal rises and advances along the spout and out of the nozzle 30.

The valve plunger 32 is operated automatically through the medium of a face cam wheel and a spring, as follows:

The valve plunger 32 is mounted on an extending arm 34, fast on a slide connecting rod 33, extending upward and through a bearing 35 formed near the lower end of the spout 29^a, and the top of the rod is fixed to the loose end of a pivot arm 36. The pivot end of this arm 36 is formed with an upright extension 37, which reciprocates vertically in a bearing 38 fixed to one side of the shelf 13. On the top of this extension 37 is mounted a roller 39, which is held up against the under face of a cam wheel 40 by a spring 43. This wheel is mounted on a short shaft 41, operating in a bracket bearing 42, fast on the shelf 13. Beneath, and axially aligned with the extension 37, is the compress spring 43 held under the tension by a collar 44^a mounted on the spout's pivot pin 44.

In operation each revolution of the cam wheel 40 releases the roller 39, whereupon the spring 43 forces the valve plunger up, and thereby closes the overflow outlet. This action confines the metal in the spout and causes it to rise and advance to and through the nozzle 30. The discharge continues while the low portion of the cam wheel is passing over the roller, but as the said roller engages with the inclined path of the cam wheel the roller is pressed down against the action of the spring 43, and the valve plunger, through its connections with the roller 39, is forced down to the open position. Then the metal is free to flow out of the spout back into the pot, through the overflow passage. This assists in keeping the metal or other liquid thoroughly mixed.

The pump supply is made far greater than the capacity of the nozzle outlet so as to get the metal quickly to, and thereafter push it under a given pressure through, the nozzle.

As soon as the spout is filled with the metal and the pressure becomes greater than the spring's action, the metal pushes the plunger down sufficiently to allow the surplus to escape back into the pot. The pressure is adjusted by raising or lowering the spring tension collar 44^a on the spout pin 44.

The cam wheel 40 is caused to revolve by a worm wheel 45 fast on the cam shaft 41. This worm wheel meshes with a worm 46, mounted loosely on the cross driving shaft 22. One end face of the worm 46 is formed with clutch jaws 47. Facing these jaws 47 on the shaft 22 is a co-acting slide clutch jaw 48 made to revolve with the shaft by a feather key. It is provided with a channel

or groove in which is located a roller 50, mounted on a rock arm 51, which arm is pivoted to an extension 52 on the bracket 42. To the lower end of this rock arm 51 is attached one end of a spring rod 53. The rod passes through an opening in the bracket 42, and is provided with a tension spring 54. The spring at all times pulls the sliding clutch jaw toward the jaws on the worm. The jaws are held out of engagement by a trip lever 55, pivoted on the rock arm 51, the short end of which engages with a pin 56, fixed in the side face of the worm wheel 45; (see Fig. 4).

It will be seen that the action of raising the long end of the trip lever 55 pushes the short end down out of engagement with the pin, and allows the spring to pull the clutch into engagement. Owing to the driving shaft 22 being in constant motion the engagement of the clutch jaws starts the worm and connecting worm wheel to revolve, carrying along the cam wheel 40. As the worm wheel nears the completion of one revolution the pin again engages the trip lever and forces the clutch jaws out of engagement, (see Figs. 1 and 4). A projection 59 is formed near the bottom of the rod 57, which is engaged on its under side by a short lever 60, mounted on a rock shaft 61, located in bearings 62 on the spout 29^a; also mounted on this rock shaft 61 is a short operating hand lever 63. The hand lever is positioned over the nozzle so as to be handy for the operator who, when a charge of metal is desired, turns the hand lever, which action pushes the short lever 60 up under the projection 59, which lifts the rod 57 attached to the trip lever 55, forcing the short end of the same from engagement with the trip pin, which act allows the clutch jaws to come into engagement and starts the cam wheel to rotate, thereby closing the overflow valve, whereupon the casting operation starts.

The cam wheel 40 is made in two parts, 40 and 40^a, one 40 is fast on the shaft 41 and 40^a is adjustable through the length of the slot 70, and held in adjustment by lock bolt 71, (see Fig. 1). By this means the amount of metal discharged can be increased or decreased according to the size of cast desired.

I have found it advisable to pivot the discharge spout so that the nozzle can be moved over the pot and warmed up before commencing casting operations, either from the heat of the metal in the pot or by tripping the pump mechanism and making several discharges through the nozzle into the pot. For this purpose I have arranged the spout so that it rests in the seat 29 of the pump casing 12. It is held in position by the spout pin 44 passing through a bracket 72, fast on the side of the bracket 14. When

in casting position it is fixed by lock bolt 73 threaded into the spout and passing through a slot in the extension 74 on bracket 72.

5. A protection shield or guard 75 is provided and arranged to circle about the outside of the gears 15 and 16. The guard is suspended from the pump casing 12, so as to leave an opening between said casing and the gears. The opening is provided so that metal passing by the agitator blades 18 in gear wheel 15 can pass out under the casing 12. To prevent too much agitation of the metal at its surface the pump casing is 15 made to cover the whole of gear wheel 15, and act to deflect the metal as it is drawn up and through the agitator. Too much agitation on the surface produces more or less dross, and it is to overcome the surface disturbance that the deflector is provided.

Although I have shown and described a preferred embodiment of the invention, I am aware of the fact that many modifications can be made therein by any person skilled in the art without departing from the scope of the invention as expressed in the claims. Therefore, I do not wish to be limited in these respects, but what I do claim is:—

30. 1. The combination with a melting pot of means for agitating molten material in said pot, and means for confining such agitation beneath the surface of said material for the purpose set forth.

35. 2. The combination of a pump, an agitator, and means for preventing substance passing up through the agitator from disturbing the surface of the substance.

40. 3. The combination with a melting pot, of means for agitating the molten material therein, a pump casing covering the agitating device to confine the agitation of the molten material beneath the surface thereof.

45. 4. The combination with a pumping means of a spout having a discharge nozzle and an overflow outlet, positive means periodically opening, and yielding means for closing, the overflow.

50. 5. In a pump, the combination of a spout, a discharge nozzle, an overflow, a wall between the spout and overflow, the top of the wall being located at a lower level than the nozzle, means whereby the pumped substance is kept above the level of said wall, and means for intermittently advancing the substance above said wall toward the nozzle.

55. 6. The combination of a continuously operating pump provided with a discharge nozzle, means for causing the flow of substance through the pump and nozzle at a uniform pressure, means for controlling the pressure, and means for stopping said flow.

60. 7. In a pump the combination with means for agitating liquid, and means for pump-

ing and delivering it, of means for automatically regulating the pumping means to receive intermittent discharges of a given quantity.

8. In a pump the combination of means 70 within for maintaining the pumped substance at a given elevation, and means for advancing a fixed amount of the substance beyond that level.

9. In a pump, the combination of a receiving chamber and means for forcing metal into the receiving chamber, with a nozzle connected with the receiving chamber for receiving metal therefrom, said nozzle having an overflow pipe which is normally open, by which metal can be discharged so as to prevent it from flowing through the nozzle, a valve for closing said overflow pipe, and a spring for forcing the valve closed, whereby the spring will yield 85 and the valve open when there is an excess of pressure within said overflow pipe.

10. In a device of the character described, the combination of a pump casing having a receiving chamber, a pair of intermeshing 90 gear wheels arranged at the entrance of said chamber and adapted to rotate in a direction to force metal into said receiving chamber, one of said wheels having inclined vanes for agitating the metal.

11. In a pump, the combination of a receiving chamber and means for forcing metal into the receiving chamber, of a nozzle connected with the receiving chamber for receiving the metal therefrom, said nozzle 100 having an overflow pipe normally open by which the metal can be discharged instead of flowing out through the nozzle, a valve for closing said overflow pipe, and means for operating said valve comprising a rod, a spring closing the valve, and a cam for forcing the rod in opposition to the spring said cam having a low concentric portion in position to permit the spring to force the valve closed.

110. 12. In a pump, the combination of a receiving chamber and means for forcing metal into the receiving chamber, of a nozzle connected with the top of the receiving chamber for receiving the metal therefrom, said nozzle having an overflow pipe normally open at the bottom by which the metal can be discharged instead of flowing out through the nozzle, a valve for closing said overflow pipe, and means for operating said valve comprising a rod extending upwardly from the valve, a spring for forcing the rod up and closing the valve, and a cam for forcing the rod down in opposition to the spring said cam having a concentric portion in position to permit the spring to force the valve up and close it.

115. 13. The combination with a pump having an overflow opening, of a valve for closing said opening, a rod for operating said valve,

- yielding means for forcing said rod into a position to close the valve, and a cam for forcing the rod into a position to open the valve in opposition to the spring, said cam 5 comprising a concentric portion of a minimum radius and an enlarged portion for operating the rod and having an adjustable member by which the extent of the enlarged portion can be adjusted.
- 10 14. The combination with a pump having an overflow opening, of a valve for closing said opening, a rod for operating said valve, and a cam for forcing the rod into a position to open the valve, said cam comprising 15 a concentric portion and an enlarged portion for operating the rod and having an adjustable member by which the extent of the enlarged portion can be adjusted.
- 15 14. The combination with a pump having an overflow opening, of a valve for closing said opening, a rod for operating said valve, and a cam for forcing the rod into a position to open the valve, said cam comprising 15 a concentric portion and an enlarged portion for operating the rod and having an adjustable member by which the extent of the enlarged portion can be adjusted.
15. In a pumping device, the combination 20 with a receiving chamber, and rotary means for filling the same, of a driving shaft, means connected with the driving shaft for operating said rotary means, a discharge nozzle having an overflow pipe therefrom 25 which when open prevents the discharge of material through the nozzle, a valve for closing said overflow pipe to permit the flow of metal through the nozzle, and means operated by said shaft for positively opening 30 said valve.
16. The combination with a continuously operating rotary pump, of a spout and nozzle together having a definite capacity for receiving liquid from the pump, and means for periodically emptying the upper part of 35 the spout while the pump continues in operation so as to keep the metal moving toward the nozzle but prevent further discharge into the nozzle.
17. In a metal pump, the combination 40 with a metal pot, of a pump therein having a seat constituting an outlet for metal and also constituting a pivot rest, and a nozzle having its inlet resting in said seat and adapted to be turned thereon, a spout pin 45 concentric with said seat and constituting a pivot in alinement therewith for the nozzle, whereby said nozzle is adapted to be turned on said seat and spout pin, a stationary bracket, and a lock bolt carried thereby 50 for holding the nozzle in its operative position.

In testimony whereof I have hereunto set my hand, in the presence of two subscribing witnesses.

CHARLES E. HOPKINS.
